UNITED STATES PATENT OFFICE.

EUGENE F. DAVENPORT, OF MELROSE, MASSACHUSETTS, ASSIGNOR TO UNITED SHOE MACHINERY CORPORATION, OF PATERSON, NEW JERSEY, A CORPORATION OF NEW JERSEY.

SKIVING-MACHINE.

1,329,294.

Specification of Letters Patent. Patented Jan. 27, 1920.

Application filed February 3, 1919. Serial No. 274,606.

To all whom it may concern:

Be it known that I, EUGENE F. DAVENPORT, a citizen of the United States, residing at Melrose, in the county of Middlesex and 5 State of Massachusetts, have invented certain new and useful Improvements in Skiving-Machines; and I do hereby declare the following to be a full, clear, and exact description of the invention, such as will enable others skilled in the art to which it 10 pertains to make and use the same.

The present invention relates to improvements in machines for skiving leather and analogous material and more particularly 15 to improved mechanism embodied in this class of machines for facilitating the feeding of the work to the skiving knife.

The object of the invention is to provide a construction which shall effectually safe- 20 guard the operator in guiding the work to the skiving knife and which shall in addition facilitate and insure the proper feeding of the work to the knife. With this object in view one feature of the invention con- 25 templates the provision of a yielding mem- ber positioned in advance of the usual presser foot and adapted to initiate the engagement of the work by the feed roll and prevent the fingers of the operator from be- 30 ing drawn into the space between the feed roll and presser foot.

A further feature of the invention con- 35 sists in the combination with the usual presser foot and feed roll of a spring mount- ed in front of the presser foot and adapted to exert a substantially uniform pressure upon work of varying thickness.

Still further features of the invention consist in certain novel features of con- 40 struction, combinations and arrangements of parts hereinafter described and claimed, the advantages of which will be obvious to those skilled in the art from the following description.

45 In the accompanying drawings illustrating the preferred form of the invention, Figure 1 represents a front elevation of the new and improved mechanism as embodied in a skiving machine; and Fig. 2 is a section upon the line 2—2 of Fig. 1 showing the method of supporting the auxiliary spring upon the presser foot and its position with relation to the feed roll.

The illustrated embodiment of the invention is conveniently shown in connection 55 with a machine of the general type disclosed in the pending application of Latham, Serial No. 216,734, filed February 12, 1918, and which comprises generally a tubular skiving knife 10, a presser foot 12, and coöperating 60 feed roll 14. The presser foot is adjustably secured in a head 15 by means of a bolt 16 received in the head and passing through a slot 17 formed in the presser foot, a knurled nut 18 threadedly connected with the rear 65 end of the bolt serving to secure the presser foot in adjusted position in the head. The feed roll in this type of machine is yieldingly supported and acts to both feed the work and retain it in position against the 70 presser foot, which in turn acts as a gage to properly locate the work with respect to the cutting edge of the knife. The most satisfactory roll for many classes of work is that disclosed in the patent to Davenport, No. 75 1,029,176, dated June 11, 1912. This roll is provided with a series of feeding teeth 20 disposed about the periphery and adapted to positively bite into the work and feed it against the edge of the knife. Although 80 this roll gives extreme satisfaction from the standpoint of feeding the work, it is somewhat dangerous on occasions for if the finger of the operator is accidentally thrust in too far between the presser foot and roll 85 serious damage may be done by the sharp feeding teeth of the roll.

The present invention contemplates a simple and effective construction adapted for embodiment in existing machines, which 90 not only facilitates the feeding of the work but which in addition effectually prevents any injury to the operator due to the feed roll. For this purpose a spring is mounted in advance of the presser foot and in such 95 a position that it initiates the gripping of the work by the feed roll in advance of the presser foot and closes the usual opening between the presser foot and feed roll into which the fingers of the operator may be 100 drawn. In the simplest and most efficient form of the invention which has yet been devised a spring having a bearing surface which conforms generally to the bearing surface of the presser foot is connected to a 105 plate adjustably supported upon the front

of the presser foot to form in effect an auxiliary foot which coöperates with the feed roll in advance of the usual presser foot. As shown in the drawings a plate 21 is provided with a series of uniformly spaced openings 22 in which are threaded a coiled spring 24, as shown in Fig. 1, having its lower portion conforming in outline to the working face of the presser foot. This 10 spring is substantially coextensive in length with the feed roll and causes the work to be engaged by the feed roll throughout its entire length. As indicated in Fig. 1, the plate 21 is provided with vertical slots 25 adapted 15 to receive screws 26 threaded in openings 27 formed in the presser foot to secure the plate in the desired position relative to the presser foot. It will be obvious that the embodiment of this construction in existing types 20 of machines involves merely the provision of the threaded openings 27 in the presser foot.

Another and extremely important advantage of the new construction is that it provides for operation upon pieces of leather which may vary in thickness throughout their width. It will be obvious to those skilled in the art that this type of machine is adapted for both skiving and splitting pieces of 30 leather, the machine as illustrated, being adjusted with the face of the presser foot substantially concentric with the cutting edge of the knife to split the leather. As some of the pieces of leather to be split have 35 a substantial variance between the thickness at different ends, this leather is engaged only at the thickest portion and the feeding action is necessarily irregular and the work in consequence must be closely watched and 40 carefully guided by the operator. This is a most prolific cause of injury as it is necessary for the operator to press the work against the feed roll at the thinner portion and incur the risk of catching the fingers 45 between the feed roll and presser foot. The auxiliary presser member or spring automatically adjusts itself to these irregularities in the thickness of the work so that all portions of the work are maintained in engagement with the feed roll and a uniform feeding action results. The particular construction shown in the drawings is especially useful in this connection as, owing to the character of the spring, the separate 50 convolutions have an independent yielding movement which results in a uniform feeding action even though the work may have a series of irregularities which would seriously interfere with the operation of the 55 machine as usually constructed.

While it is preferred to employ the specific construction and arrangement of parts shown and described, it will be understood that this construction and arrangement is 60 not essential except so far as specified in

the claims, and may be changed or modified without departing from the broader features of the invention.

The invention having been described, what is claimed is:

1. A skiving machine comprising a tubular knife, a presser foot, a coöperating feed roll, and a yielding member positioned in advance of the presser foot and adapted to initiate the engagement of the work by the 75 feed roll.

2. A skiving machine comprising a tubular knife, a presser foot, a coöperating feed roll, and a spring supported upon the front of the presser foot and adapted to engage 80 the work in advance of the presser foot to initiate the engagement of the work by the feed roll.

3. A skiving machine comprising a tubular knife, a presser foot having a working 85 face substantially concentric with the curvature of the knife, a feed roll coöperating with the presser foot, and a spring supported upon the front of the presser foot and having a bearing surface extending substantially 90 in the direction of curvature of the working face of the presser foot.

4. A skiving machine comprising a tubular skiving knife, an unyielding presser foot, a feed roll having a curved periphery coöperating with the presser foot, and an auxiliary yielding presser member supported in advance of the foot and having a bearing surface which conforms generally in curvature to the curvature of the feed roll. 100

5. A skiving machine comprising a skiving knife, a presser foot and feed roll coöperating with the knife to split sheets of leather, and an auxiliary presser member having independently yielding portions 105 adapted to engage the work in advance of the presser foot and cause all portions of the work to be gripped by the feed roll.

6. A skiving machine comprising a skiving knife, a presser foot and feed roll coöperating to guide and feed the work to the knife, a plate adjustably secured to the front of the presser foot and having a series of openings formed in the lower edge, and a coiled spring threaded in the plate and 110 adapted to bear at its lower edge upon the work and initiate the engagement of the work by the feed roll. 115

7. A skiving machine comprising a skiving knife, a presser foot, a feed roll coöperating with the presser foot and having a series of feeding teeth disposed about the periphery to positively bite into the work, and a yielding guard supported upon the front of the presser foot in operative relation to the surface of the feed roll to initiate the feed of the work by the roll and substantially close the space between the presser foot and feed roll. 120

8. A skiving machine comprising a skiv- 130

ing knife, a stationary presser foot, a feeding member coöperating with the presser foot, a plate secured to the front of the presser foot and having provision for vertical adjustment, and a coiled spring connected to the lower edge of the plate and adapted to present a bearing surface curved in substantial conformity with the curvature of the presser foot.

5 10. A skiving machine comprising a tubular skiving knife, a presser foot having a

working face conforming generally to the curvature of the knife, a coöperating feed roll, and a spring supported upon the front of the presser foot and having a bearing portion which extends in the direction of curvature of the working face of the presser foot and is adapted to yieldingly engage with the work and cause all portions of the latter throughout its width to be gripped by the feed roll.

15 20. EUGENE F. DAVENPORT.
